UNITED STATES PATENT OFFICE.

RICHARD J. BEALL, JR., OF WASHINGTON, DISTRICT OF COLUMBIA, ASSIGNOR TO THE SIMPLEX CONCRETE PILING COMPANY, OF WASHINGTON, DISTRICT OF COLUMBIA, A CORPORATION OF THE DISTRICT OF COLUMBIA.

REMOVABLE PILE FOR FORMING CONCRETE PILING.

1,127,392.

Specification of Letters Patent.

Patented Feb. 9, 1915.

Application filed April 9, 1904, Serial No. 202,414. Renewed June 20, 1908. Serial No. 439,592.

To all whom it may concern:

Be it known that I, RICHARD J. BEALL, Jr., a citizen of the United States, residing at Washington, in the District of Columbia, 5 have invented a Removable Pile for Forming Concrete Piling, of which the following is a specification.

My invention relates to that method of forming piles of concrete or cement which 10 consists in first driving a preparatory pile into the ground, then withdrawing said preparatory pile, and then filling the opening formed thereby with fluid or plastic concrete or cement which when it becomes set 15 will form the permanent pile.

The object of my invention is to so construct the removable preparatory pile that the same can be driven or withdrawn with the exercise of much less power than is required 20 when piles of this class as heretofore constructed are used.

In the accompanying drawing: Figure 1 is a vertical section of a preparatory pile and point constructed in accordance with 25 my invention, showing the character of the opening formed in the ground by said pile. Fig. 2 is a view showing a modification of the point of the pile. Fig. 3 is a view showing the permanent pile produced by filling 30 the opening with cement or concrete after the preparatory pile has been withdrawn.

For the purpose of forming in the ground openings for the reception of concrete or cement to constitute permanent piling the 35 use of an ordinary wooden or metal pile of cylindrical form or tapering inwardly from top to bottom is objectionable, for the reason that the frictional hold of the earth upon the sides of the pile is such that said pile 40 cannot be driven beyond a limited distance without the exercise of destructive force and cannot be withdrawn after being driven without the exercise of still greater force, the frictional hold of the earth upon the pile 45 being now assisted by atmospheric pressure, owing to the fact that the withdrawal of the pile tends to create a partial vacuum in the opening left thereby. For this reason various forms of collapsible piles have been 50 proposed; but such piles, owing to their sectional character, are necessarily limited in strength, and, moreover, do not overcome the objection of resistance due to the frictional

hold of the earth thereupon while they are being driven.

In carrying out my invention, therefore, I form on the pile or provide the pile with a point which is greater in diameter than the pile itself, so that the frictional hold of the earth both in driving and withdrawing 60 the pile is restricted to the limited area presented by this expanded point, with the result that the pile can be driven to any desired depth without unduly increasing the frictional hold of the earth upon the pile 65 and can also be withdrawn with the exercise of a relatively limited amount of power.

The pile shown in Fig. 1 consists of a metal tube, although it may be a solid pile of wood or metal, if desired, this pile being 70 provided at the top with a suitable driving head 2, and at the bottom with a point 3, which is of so much greater diameter than the pile 1 that there is no likelihood of the latter coming in contact to any material extent with the walls of the opening formed by driving the pile. The horizontal cross-section of the enlarged point approximates that of the body of the pile, but is of somewhat greater area. Hence the strains on 80 the pile during the driving of the same are distributed with substantial equality about the periphery of the pile, and there is no tendency of the pile to deflect from its proper line.

The point 3 of the pile is reduced in diameter at the top, so as to provide a shoulder for engagement with the lower end of the pile, and this reduced portion of the point can be secured to the lower end of the pile 90 by rivets 4, or other suitable fastenings, or, if desired, the pile and its point may be in one piece. The point 3 has a tapered lower end and also by preference tapers from its portion of greater diameter inwardly to the 95 shoulder upon which rests the lower end of the pile 1. Hence no abrupt shoulders are presented to the earth either in driving or withdrawing the pile, the earth during the driving operation being displaced laterally 100 by force, which is exerted evenly in all directions from the axial center of the pile, while the upper taper of the point serves in like manner to laterally press upon the walls of the opening when the pile is being withdrawn if said walls or any portion of the 105

same have been displaced inwardly after the point has passed the same in driving the pile.

5 The point 3 (shown in Fig. 1) is hollow or should have an opening communicating with the lower end, so as to provide for the downward passage of air through the pile when the latter is being withdrawn, thus preventing the formation of any partial 10 vacuum in the space below the point of the pile, and thereby relieving said point from any frictional contact of the walls of the opening thereupon due to atmospheric pressure.

15 Of course it will be understood that in withdrawing the pile the driving-head 2 is removed or other means are provided for permitting free ingress of air to the interior of the pile.

20 The opening at the bottom of the point 3 is preferably provided with a valve opening downwardly, this valve in the present instance consisting of a detachable plug 5, which will be released as soon as the withdrawal of the pile is attempted.

25 The point 3 can be made of wood, iron, steel, concrete, combinations of the same, or, in fact, of any material which will withstand the shock of driving.

30 Where the relief opening through the point is employed, said point may in forming openings in some kinds of ground be of the same diameter as the pile, as indicated in Fig. 2, in which 3^a designates the 35 point which is connected to the pile 7 as in Fig. 1, by rivets 8, though as heretofore stated any other fastening means may be employed to connect the point to the pile, or said point formed integrally with the 40 body of the pile. Even in the instance shown in said Fig. 2 the friction upon the pile due to atmospheric pressure in withdrawing the same is overcome by the opening through the pile and opening at the 45 point.

Having thus described my invention, what I claim and desire to secure by Letters-Patent, is:

50 1. As a device for forming in the ground an opening for the subsequent reception of concrete or other fluid or plastic material, a removable preparatory pile terminating in a pointed hole forming end or head exceeding in size or diameter the greatest 55 diameter of any part of the pile stem, whereby in withdrawing the pile any friction between any part of the pile stem and the wall of the hole formed thereby is avoided, except at the head.

60 2. As a device for forming in the ground an opening for the subsequent reception of concrete or other fluid or plastic material, a removable preparatory pile terminating in a pointed hole forming end or head exceeding in size or diameter the greatest 65

70 diameter of the body of the pile and having a tapering portion between the pile body and the largest portion of the head, which tapering portion is continuous with the surface of the head, thereby presenting a smooth 75 unobstructed surface, whereby in withdrawing the pile friction between any part of the pile and the wall of the hole formed thereby is avoided, except at the head, and the upper tapering portion of the latter avoiding 80 defacements or injury of the wall of the opening.

85 3. As a device for forming in the ground an opening for the subsequent reception of concrete or other fluid or plastic material, a removable preparatory pile having a fixed point with an opening extending through the point, whereby air can enter the space below the point as the pile is withdrawn, substantially as specified.

90 4. As a device for forming in the ground an opening for the subsequent reception of concrete or other fluid or plastic material, a removable preparatory pile having an opening therethrough, and a point secured to the pile and having a relief-opening therein, whereby air can enter the space below the point as the pile is withdrawn, substantially as specified.

95 5. As a device for forming in the ground an opening for the subsequent reception of concrete or other fluid or plastic material, a removable pile having an opening therein which extends through the point, and a valve which closes said opening during the 100 driving of the pile, substantially as specified.

105 6. As a device for forming in the ground an opening for the subsequent reception of concrete or other fluid or plastic material, a removable pile having an opening therethrough, a point secured to the pile and also having a relief-opening therein, and a valve which closes said opening in the point during 110 the driving of the pile, substantially as specified.

115 7. As a device for forming in the ground an opening for the subsequent reception of concrete or other fluid or plastic material, a removable pile having an enlarged point, and an opening through which air can enter 120 the space below the point of the pile as the latter is withdrawn, substantially as specified.

125 8. As a device for forming in the ground an opening for the subsequent reception of concrete or other fluid or plastic material, a removable preparatory pile having an opening therethrough and an enlarged point secured to said pile and also having a relief-opening therein through which air can enter 130 the space below the point as the pile is withdrawn, substantially as specified.

9. As a device for forming in the ground an opening for the subsequent reception of concrete or other fluid or plastic material,

a removable preparatory pile having an enlarged point, an opening extending through the point of the pile, and a valve which closes said opening during the driving of the pile, substantially as specified.

5 10. As a device for forming in the ground an opening for the subsequent reception of concrete or other fluid or plastic material, a removable preparatory pile having an opening therethrough, an enlarged point secured to the pile and also having a relief-

opening therein, and a valve which closes said relief-opening during the driving of the pile, substantially as specified.

In testimony whereof I have signed my 15 name to this specification in the presence of two subscribing witnesses.
